EXHIBITING OR DISPLAY DEVICE

John Sneed, Detroit, Mich., assignor, by mesne assignments, to Poster Machines Corporation, Detroit, Mich., a corporation of Michigan

Application March 7, 1940, Serial No. 322,779

12 Claims. (Cl. 40—36)

This invention relates to exhibiting or display devices and in particular to changeable exhibiting or displaying devices wherein a plurality of exhibited or display objects are displayed in sequence, such objects including cards, pictures, posters, signs, or the like.

One object of this invention is to provide a changeable exhibiting or displaying device wherein a plurality of exhibited or display objects are displayed in sequence, means being provided for positively moving each object into the path of the conveying mechanism.

Another object is to provide a changeable exhibiting device wherein feeding mechanism is driven in timed relationship with conveying mechanism so that the exhibited objects are positively moved into the path of the conveyor mechanism so as to be intercepted and conveyed at predetermined intervals of time.

Another object is to provide a changeable exhibiting device for sequentially displaying a plurality of exhibited objects, the exhibited objects having projections which are positively urged by feeding mechanism into the paths of conveyors, these projections being again engaged, after conveying has taken place, by an intercepting mechanism which directs them into guides along which they are again advanced to the feeding and conveying mechanism.

Another object is to provide a changeable exhibiting device, as set forth in the preceding objects, wherein the feeding and intercepting mechanism includes an element which in one direction of its motion advances an exhibited object to the conveying position, and in another direction of its motion intercepts such an object and removes it from the conveyor after the desired conveying has taken place, this element being driven in timed relationship with the conveyors.

Another object is to provide a changeable exhibiting device as set forth in the preceding objects wherein a detent cooperates with the object feeding mechanism so as to permit only one object to be feed to the conveyors at a given time.

Another object is to provide a changeable exhibiting device adapted to sequentially display a plurality of exhibited objects in the form of cards, pictures, panels, signs, or the like, wherein the top portions of the objects are engaged and conveyed by conveyors at predetermined points of time and moved from the display position into a storage position, mechanism being provided for separating the bottom parts of the exhibited objects, this separating mechanism being preferably

driven in timed relationship with feeding mechanism which feeds the objects to the conveyors.

Another object is to provide a changeable exhibiting device as set forth in the preceding objects wherein the exhibited object, after being conveyed from the display position toward the storage position, is permitted to move relatively to the conveyors, such as to drop by gravity, a short distance, so that the object is released from engagement by the conveyors so that it can be disposed upon the guides, preferably by interceptor mechanism, to be fed to the conveyors again after the objects ahead of it have been displayed.

Another object is to provide a changeable exhibiting device, means being provided for moving a plurality of exhibited objects from a display position to a storage position, each object having opposite sides which are displayed in alternate cycles of the device, one side being inverted relatively to the other side, the objects being moved into the paths of conveyors by mechanism driven in timed relationship therewith, whereupon the objects are conveyed from the display position into a storage position from which they are again moved into the path of the feeding mechanism for repeated display, the feeding mechanism being preferably actuated by cam elements so as to give a simple and silent operation as well as to positively hold the objects in their desired positions.

Another object is to provide a changeable exhibiting device, as set forth in the preceding objects, wherein the objects are displayed in a tilting arrangement relatively to the vertical, thereby enabling the objects to be more conveniently seen by persons below the device, as well as facilitating the illumination of the objects by illuminating elements placed in the lower part of the device below the objects.

In the drawings:

Fig. 1 is a front elevation, partly in section, along the irregular line 1—1 in Fig. 2, of a preferred embodiment of a changeable exhibiting device according to the invention, with the housing removed and certain portions broken away to show the mechanism more clearly;

Fig. 2 is a vertical section taken along the line 2—2 in Fig. 1, showing the parts in the feeding position wherein the feeding mechanism has advanced one of the exhibited objects into the path of the conveyor;

Fig. 3 is a vertical section similar to Fig. 2, but showing the parts in the intercepting position, wherein the exhibited object has been con-

veyed from the display position toward the storage position and is about to be intercepted and removed from the conveyer;

Fig. 4 is a horizontal section along the irregular line 4—4 in Fig. 2, showing the conveyor driving and feeder timing mechanism;

Fig. 5 is a horizontal section along the irregular line 5—5 in Fig. 2, showing details of the feeding and intercepting mechanism;

Fig. 6 is a horizontal section along the line 6—6 in Fig. 2, showing details of the supporting structure;

Fig. 7 is a horizontal section along the line 7—7 in Fig. 2, showing details of the mechanism at the lower ends of the exhibited objects, such as the posters or signs being displayed;

Fig. 8 is an inclined section, taken along the line 8—8 in Fig. 3, showing details of the feeding mechanism;

Fig. 9 is an enlarged cross-section through the end of one of the exhibited objects showing one way of attaching the card, sign, picture, poster, or the like, to the rod which passes along the end of the object; and

Fig. 10 is a vertical section taken along the line 10—10 in Fig. 1 and showing details of the cam for operating the feeding mechanism.

General arrangement

In general, the changeable exhibiting or display device of the invention consists of a housing having a pair of endless conveyors with hooks thereon adapted to pick up and convey the projecting ends of exhibited objects, such as posters, pictures, signs, or the like. When thus picked up at the display position, the posters or signs are conveyed over suitable guide rollers to a storage position at the back of the housing.

Before the posters or signs reach the storage position, however, they are permitted to drop a short distance, preferably by gravity, so that they fall out of engagement with the conveyor hooks. Upon being thus released from the conveyors, the poster, sign, or the like, is intercepted by suitable mechanism and directed into an inclined guide along which it moves toward the display position.

When the exhibited object, such as a poster, nears the end of the inclined guide, it is engaged by a feeder which feeds it into the path of the conveyor hooks. Here it remains for the display period and in the display position until the conveyor hooks arrive opposite the projections at the ends of the poster. When this occurs, the poster or sign is again conveyed by the conveyor from the display position to the storage position and the foregoing cycle is repeated.

Each exhibited object is in the form of a sheet or panel and is provided with pictures, signs or the like, on its opposite sides, one being inverted relatively to the other. Thus in the changeable exhibiting of this invention, the device will display twice as many signs or pictures as there are sheets or panels in the device.

The opposite ends of the panels or sheets are provided with transverse rods, the ends of which project so as to provide engagement between feeding, conveying, intercepting and guiding mechanism. At the upper end of the housing a fixed detent cooperates with the feeder so as to permit only one object at a time to pass into the feeder and be moved thereby into the path of the conveyor. At the lower end of the housing, there is provided a separator which cooperates with the feeder and is preferably driven in timed relationship therewith to release only one object

at a time, namely, the object which has reached the display position. This arrangement prevents the jamming or chafing of the various panels or sheets, thereby protecting their surfaces as well as preventing a breakdown of the device. The signs or posters, while in the display position, are tilted relatively to the vertical so as to be clearly visible to persons viewing them from beneath, as well as to provide convenient means for illuminating the posters or signs by sources of illumination placed in the bottom part of the housing. The housing itself may thus be made very compact because the storage space is immediately behind the display position and each poster or sign is moved over the top of the mechanism from one position to the other.

Driving and conveying mechanism

Referring to the drawings in details, Figs. 1 to 3 show the driving and conveying mechanism and the supporting structure therefor. The device is supported upon a base 10 having a back 11, a removable top 12, front 13 and sides 14 being shown by chain lines. In Figs. 1, 2 and 3, these are removed for the purpose of more clearly showing the mechanism normally enclosed therein. The front 13 is provided with inwardly directed portions 15 and 16 leading to a display aperture 17 through which the exhibited objects, such as posters or signs, are viewed by persons in front of the machine. The portion 16 is preferably removed in the event the device is illuminated by artificial light, and electric lights are placed in the lower part of the housing, together with suitable reflectors.

The changeable exhibiting device of the invention is supported by a framework consisting of lower side plates 18 mounted on the base 10 and interconnected by horizontal angle members 19, the latter being secured to the former as at 20. Secured to and rising from the side plates 18 are the oppositely facing front and rear angle uprights 21 and 22, respectively. Midway of their heights the uprights 21 and 22 are interconnected by the bent strips 23 (Figs. 2 and 6) which in turn carry the supports 24 to which are secured the upright guides 25 for the ends of the posters or signs being exhibited. The upper ends of the uprights 21 and 22 are secured to and interconnected by the upper side plates 26 (Figs. 2 and 3) which serve to support the feeding, guiding and conveying mechanism as described below. The upper side plates 26 are interconnected by the horizontal angle members 27 secured thereto as at 28.

Mounted on the base 10 (Fig. 1) is a driving motor 28 having a shaft 31 carrying a pulley 32. The pulley 32 drives a pulley 33 upon the input shaft 34 of a reduction gear box 35 by means of a belt 36. The reduction gear box 35 preferably contains a worm 36 driving a worm gear 37 mounted upon a sprocket shaft 38 which is rotatably supported at its opposite ends in the lower side plates 18. The mechanism at the opposite ends of the machine is substantially duplicated and bears corresponding reference numerals, hence it will be sufficient to describe and illustrate one end only of the machine shown in Figs. 4 to 10. Mounted on the sprocket shaft 38 and secured thereto are lower sprockets 39 (Figs. 1 and 7). The sprocket shafts also pass through the brackets 49 which are secured at 41 to the lower side plates 18 and support the lower ends of the upright guides 25. The sprockets 39 carry sprocket chains 42 which mesh with the upper

sprockets 43 mounted on the stub shafts 44 (Figs. 1 and 4). The sprockets 43 are drivingly secured to the shaft 44 by the pins 45. The shafts 44 are rotatably supported in the bearings 46 mounted in the upper side plates 26 (Fig. 4).

Loosely mounted for free rotation upon the inwardly facing ends of the shafts 44 are discs 47 constituting the opposite ends of a guide roller 48. The latter is preferably constructed of light weight material and serves to support the posters or signs as they are carried over the top of the mechanism from the display position to the storage position. The shaft 44 also passes through the upper end of a plate-like member 49 which constitutes the upper portion of the guides 25, the lower portion 50 being mounted on the bracket 60 in the manner previously described.

Mounted on the sprocket chains 42 are the upper and lower conveyor hooks 51 and 52, respectively (Figs. 5 and 7). These conveyor hooks 51 and 52 are spaced apart by approximately the vertical dimension of the sign or poster being exhibited and their inner ends pass along paths extending longitudinally and vertically within the angle portion of the upright guides 25. The posters, signs or the like, are provided with transverse rods 53, the ends of which project into the sheets of the conveyor hooks 51 and 52 so as to be engaged thereby. The exhibited object, generally designated 54 (Fig. 9), preferably consists of a sheet 55 securely clamped, in any suitable way, between the members 56 which encircle the rods 53.

Secured to the outer ends of the upper sprocket shafts 44, as at 57, are pinions 58 (Figs. 4 and 10) which mesh with the internal ring gears 59 secured as at 60 to the cams 61. Each cam 61 is mounted upon a threaded hub 62 by means of a nut 63 and is freely rotatable upon a fixed shaft 64 having a head 65 by which it is mounted in the aperture 66 of the upper side plate 26. A nut 67, threaded upon the shaft 64, serves to retain the latter in position. The cam hub 62 is itself retained in position by the retaining bolt 68 threaded into the outer end of the fixed shaft 64.

Feeding, guiding and intercepting mechanism

The mechanism for feeding the various signs, posters or other exhibited objects, to the conveyors is operated in timed relationship with the cams 61. To this end, the cams 61 are engaged by cam rollers 70 rotatably mounted upon pins 71 on arms 72 (Figs. 8 and 10). The latter are secured as at 73 to the shafts 74 which in turn are pivotally supported in the bearings 75 and 76 inserted in apertures 77 and 78 in the members 29 and 28, respectively. Tubular spacing element 79 encircles the shaft 74 between the bearings 75 and 76.

Secured, as at 80, to the opposite end of the arm 72 from the roller 70, is a coil spring 81 (Fig. 8) which in turn is secured as at 82 to one of the uprights 21 (Fig. 2). This spring 81 constantly urges the roller 70 into engagement with the periphery of the cam 61. The opposite end of the shaft 74 carries an arm 83 welded or otherwise firmly secured thereto. The outer end of this arm 83 is provided with a pivot pin 84 upon which the feeder 85 is pivotally mounted (Figs. 2, 5 and 8).

The feeder 85 (Fig. 2) also pivots upon a pivot pin 86 mounted upon one arm of a bell crank 87 which in turn is mounted upon a pivot shaft 88,

the opposite end of which passes through the aperture 89 in the side plate 26 (Fig. 5) and which is secured thereto by the nut 90 threaded upon the outer end thereof. The arm 83 and the corresponding arm of the bell crank 87 are of substantially equal length between their pivots and are also substantially parallel so that the feeder 85 moves to and fro when the cam roller 70 rises and falls under the influence of the cam 61. The outer end of the feeder 85 is provided with a notch 91 into which the ends of the rods 53 are adapted to drop.

A fixed detent 92 (Fig. 2) secured by the screws 93 to the upper side plate 26 serves to permit only one rod 53 to drop into the notch 91 at a given time. A slot 94 in the fixed detent 92 permits the vertical adjustment of the latter. The opposite end of the feeder 85 is bent upwardly to form an intercepting portion 95 which moves into the path of the conveyor chain 42 toward the back 11 when the feeder 85 is in its retracted position. The intercepting portion 95, as hereinafter explained, serves to engage rod 53 which has passed over the top of the guide roller 48 and directs it upon an inclined guideway 96 (Figs. 2 and 5) secured to the member 49.

The rods 53 move down this inclined guideway toward the fixed detent 92, under the influence of gravity, and the foremost rod 53 drops into the notch 91 when the feeder 85 is in its retracted position. The lower arm of the bell crank 87 is provided with a pivot pin 97 carrying a downwardly directed separator rod, the lower end of which is pointed as at 98. This rod 98 is guided by the member 100 (Fig. 2) secured to the upright guide 25 (Fig. 1). This separator rod serves to separate the foremost lower rod 53 from the remaining rods while they are suspended within the apparatus. By these connections the separator rod 98 is operated in timed relationship with the reciprocation of the feeder 85.

The lower part of the apparatus contains lower guides 101, one on each side, and secured as at 102 to each lower side plate 18. These guides 101 serve to guide the lower rods 53 of the posters or signs 54 as the latter are conveyed upwardly by the conveyor hooks 51. It will be seen from Fig. 2 that when the posters or signs 54 are in either a display or a storage position, their planes are inclined to the vertical. Thus, the pull of gravity upon the lower rods 53 causes the foremost of these to be urged against the guides 101 while the upper rod 53 is being conveyed upwardly by the upper conveyor hook 51. The distance between the bottoms of the curved portions of the conveyor hooks 51 and 52 is somewhat less than the length of each poster or sign 54, namely the distance between each upper and lower rod 53, hence the lower rod 53 will swing into position beneath the curved portion of the lower conveyor hook 52 while the upper rod 53 is conveying the upper poster 54 upward.

The rearward portion of the upright guides 25 (Fig. 2) terminates at a rounded corner 103 beyond which it is inclined forwardly and downwardly in an inclined portion 104. This forward portion 103 enables the rearmost lower rod 53 to move forwardly (Fig. 3) out of the way of the conveyor hook 51 as the conveyor hook 52 moves over the top of the apparatus. The slightly shorter separations of the conveyor hooks 51 and 52 than the length between the upper and lower rods 53, causes the poster to

drop under the force of gravity by an amount equal to the difference between these two distances so that the lowermost rod 53, which has heretofore been below the curved portion of the conveyor hook 52, now drops into this curved portion while the upper rod 53, which has now become the lower rod, drops out of the corresponding curved portion of the conveyor hook 51 and slides around the corner 103 out of the way of the downwardly traveling conveyor hook 51. A pair of lower rearward guides 105, secured as at 106 to the rearward uprights 22, serve to fend the lower rods 53 forwardly in the event that they should tend to start swinging, pendulum-like, as they move downwardly.

From Figs. 4 and 7, it will be seen that the upper and lower sprockets 43 and 49 are of different diameters. In order to cause the conveyor chain hooks 51 and 52 to clear the rearmost lower rod 53 (Fig. 3), there are provided idler sprockets 107 mounted on studs 108. The studs 108 are mounted in blocks 109 (Fig. 7) and secured thereto by the nuts 110 threaded upon the outer ends thereof. The blocks 109 are slideable vertically in slots 111 in the lower side plates 18. Each block 109 is held in its adjusted position by means of an adjusting screw 112 threaded through the horizontal portion 113 of the bracket 114 which in turn is secured to the lower side plates 18. Each adjusting screw 112 has a lock nut 115 by which it may be held in any adjusted position. The horizontal portion 113 terminates in a downwardly bent arm 116 to which the lower portion 50 of the guide structure 25 is secured, as by the screw 117 (Fig. 7). The outer ends of the rods 53 are rounded as at 118 so as to permit them to engage the guide structure 25 with the least friction.

Operation

The operation of the device has already been explained, in part, in connection with the description of the construction thereof. The device is prepared for operation by placing a plurality of signs, posters or pictures 54, generally called the exhibited objects, upon the inclined guideways 96 with the upper rods 53 resting upon these guideways. The lower rods 53 hang suspended freely from the sheet portions 55 with the foremost lower rod 53 in contact with the inclined lower guides 101. The conveyor chains 42 are adjusted upon their sprockets and the cams 61 correspondingly adjusted so that the oscillation of the feeder 85 will take place in proper timed relationship with the motion of the conveyor hooks 51 and 52.

The machine is then started in operation by energizing the motor 30, rotating the conveyor sprocket shaft 38 and the conveyor sprocket 39. As the conveyor hooks 51 move upwardly, the large diameter portion of the cam 61 engages the cam roller 70 and swings the arm 72 downwardly, rotating the shaft 74 and the arm 83 forwardly. This reciprocates the two feeders 85 in a forward direction and advances the foremost upper rod 53 of the foremost poster or sign 54 into the paths of the uppermost conveyor hooks 51. The position of the parts at this portion of the cycle of operation is shown in Fig. 2. The falling upper rods 53 are prevented from moving forward by the fixed detent 92. The exhibited object 54, such as a sign, poster or picture, remains in this forward or display position while the cam roller 70 rides upon the large diameter portion of the cam 61 (Fig. 10).

Meanwhile, the conveyor hooks 51 have moved upwardly to positions on the same level as the feeders 85 and pick up the ends of the upper foremost rod 53. As the conveyor hooks 51 move upwardly around the upper sprockets 43, they pull the foremost poster or sign 54 over the freely rotatable roller 48 and down upon the rearward side of the machine. As the lower rod 53 of the foremost poster or sign 54 passes over the top of the roller 48, the weight of the sign or poster 54 and of the other rod 53 which has now become the lower rod, causes the poster to drop downwardly a short distance so that the leading rod 53 drops out of the conveyor hook 51 and moves around the corner 103 (Fig. 3), while the trailing rod 53 moves into the curved portion of the conveyor hook 52. The parts are now in the positions shown in Fig. 3. The leading rod 53 thus moves out of the paths of the conveyor hooks 51 and moves downwardly.

Meanwhile, the cam 61 has been rotating so that the roller 70 arrives at the flat spot thereon (Fig. 10) and, accordingly, swings the arms 72 and 83 (Figs. 3, 5 and 8) upwardly and rearwardly. This action reciprocates the feeders 85 rearwardly into the position shown in Fig. 3. The intercepting portions 95 are thereby moved rearwardly into the paths of the ends of the trailing rod 53. When the conveyor hooks 52 arrive on the same level as the intercepting portions 95, the latter engage the ends of the rods 53 and remove them from the conveyor hooks 52. As the latter continue to move downwardly, the rod 53 is guided onto the inclined guideways 96 as shown in Fig. 3.

In the meantime, the bell cranks 87 have been reciprocated so as to raise the separator rods 98, thereby permitting another lower rod 53 to move forwardly into engagement with the guides 101. The rearward reciprocation of the feeders 85 also has brought the notches 91 thereof into the positions shown in Fig. 3, back of the fixed detent 92. The ends of the foremost rod 53 may then drop into the notches 91 ready to be moved forward upon the next reciprocation of the feeders 85.

While a specific embodiment of the invention has been described and illustrated, it will be understood that various modifications may be made within the scope of the appended claims without departing from the spirit of the invention.

What I claim is:

1. An exhibiting or display device comprising a plurality of display objects, conveying means engageable with said display objects for conveying the same from a display position to a storage position, feeding means for feeding one edge of each of said display objects from said storage position into engageability with said conveying means, means for operating said feeding means in timed relationship with said conveying means, and means associated with said feeding means for selectively separating and releasing an opposite edge of the display object being fed from other display objects in said storage position, said separating means being intermittently interposed between the display object being fed and the other display objects whereby to permit only the foremost display object to be fed while holding back the other display objects.

2. An exhibiting or display device comprising a plurality of display objects, conveying means engageable with said display objects for conveying the same from a display position to a storage

position, feeding means for feeding the upper portion of each of said display objects from said storage position into engageability with said conveying means, means for operating said feeding means in timed relationship with said conveying means, and means operatively connected to said feeding means and operable in timed relationship therewith for selectively separating and releasing the lower portion of the display object being fed from other display objects in said storage position, said separating means being intermittently interposed between the display object being fed and the other display objects whereby to permit only the foremost display object to be fed while holding back the other display objects.

3. An exhibiting or display device comprising a plurality of display objects, an endless conveyor engageable with said display objects for conveying the same from a display position to a storage position, feeding means for feeding the upper portion of each of said display objects from said storage position into engageability with said conveying means, spaced upper and lower carriers secured to said conveyor for releasably holding the upper and lower portions of said display objects on said conveyor, and means for operating said feeding means in timed relationship with said conveying means, the upper portion of said display object in the display position being held in a forwardly inclined position relatively to the lower portion, whereby the lower portion swings into engagement with the lower carrier in response to the force of gravity.

4. An exhibiting or display device comprising a plurality of display objects, an endless conveyor having means engageable with said display objects for conveying said display objects from a display location to a storage location, guiding means extending from said storage location toward said display location, a feeder arranged to feed said display objects from said guiding means to said conveyor, and a rotary cam operatively connected to said feeder and actuated in timed relationship with said conveyor for operating said feeder.

5. An exhibiting or display device comprising a plurality of display objects, an endless conveyor having an upwardly movable section near the front of said device and a downwardly movable section near the rear thereof, means on said conveyor engageable with said display objects for conveying said display objects from a display location near the front of the device upwardly to a storage location nearer the rear of the device, guiding means for said display objects extending from said storage location toward said display location, a feeder arranged to feed said display objects from said guiding means to said conveyor, means for operating said feeder in timed relationship with said conveyor, and an interceptor connected to and projecting rearwardly from said feeder and movable therewith into the path of the rearward section of the conveyor to intercept said display objects after they have been conveyed by said conveyor from said display location to said storage location.

6. An exhibiting or display device comprising a plurality of display objects, an endless conveyor having an upwardly movable section near the front of said device and a downwardly movable section near the rear thereof, means on said conveyor engageable with said display objects for conveying said display objects from a display location near the front of the device upwardly to a

storage location nearer the rear of the device, guiding means for said display objects extending from said storage location toward said display location, a horizontal reciprocable feeder arranged to feed said display objects from said guiding means to said conveyor, means for operating said feeder in timed relationship with said conveyor, and an interceptor projecting upwardly and rearwardly from said feeder and movable therewith into the path of the rearward section of the conveyor for removing said display objects from said rearward section of said conveyor and depositing the same on said guiding means.

15. 7. An exhibiting or display device comprising a plurality of display objects, an endless conveyor having means engageable with said display objects for conveying said display objects from a display location to a storage location, a guideway extending from said storage location toward said display location, a feeder arranged to feed said display objects from said guideway to said conveyor, said feeder having a recess for receiving a portion of a display object, means for operating said feeder in timed relationship with said conveyor, and a stationary detent adjacent said feeder and guideway and defining with said recess a space capable of receiving only one of said display object portions at one time in the receiving position thereof but incapable of receiving the same in other positions of said feeder whereby to pass one only of said display objects at a time from said guideway to said feeder whereby to pass one only of said display objects at a time from said guideway to said feeder and thence to said conveyor.

30. 8. An exhibiting or display device comprising a plurality of display objects, an endless conveyor having an upwardly movable front section and a downwardly movable rear section, means engageable with said display objects for conveying said display objects from a display location near the front of the device to a storage location nearer the rear thereof, guiding means for said display objects extending from said storage location toward said display location, a feeder arranged to feed said display objects from said guiding means to said conveyor, and means for operating said feeder in timed relationship with said conveyor, said display object engaging means including projecting display object carriers secured to said conveyor in spaced relationship along said conveyor at separations less than the corresponding dimensions of the display object conveyed thereby whereby to permit the display object to drop by gravity from one projecting carrier to the other as the display object passes over the top of the device while being conveyed.

35. 9. An exhibiting or display device comprising a plurality of display objects, an endless conveyor having an upwardly movable front section and a downwardly movable rear section, means engageable with said display objects for conveying said display objects from a display location near the front of said device to a storage location nearer the rear thereof, guiding means for said display objects extending from said storage location toward said display location, a feeder arranged to feed said display objects from said guiding means to said conveyor, and means for operating said feeder in timed relationship with said conveyor, said display object engaging means including a pair of oppositely-directed projecting hocked members secured to said conveyor in spaced relationship along said conveyor, said projecting

hooked members being spaced apart a distance less than the corresponding dimension of the display object conveyed thereby whereby to permit the display object to drop by gravity from one projecting hooked member to the other as the display object passes over the top of the device so as to release the display object from engagement with said other hooked member.

10. An exhibiting or display device comprising a plurality of display objects, an endless conveyor or having an upwardly movable front section and a downwardly movable rear section, spaced display object carriers thereon engageable with said display objects for conveying each display object from a display location near the front of the device around to a storage location nearer the rear thereof, display object guiding means extending from said storage location toward said display location, a horizontally reciprocable feeder arranged to receive and feed one display object at a time from said guiding means to said conveyor and having a display object engaging portion movable from a loading position adjacent the forward end of said guiding means to an unloading position adjacent the path of said carriers on said conveyor, and feeder operating mechanism connected in timed relationship with said conveyor.

11. An exhibiting or display device comprising a plurality of display objects, an endless conveyor or having an upwardly movable front section and a downwardly movable rear section, spaced display object carriers thereon engageable with said display objects for conveying each display object from a display location near the front of the device around to a storage location nearer the rear thereof, display object guiding means extending

from said storage location toward said display location, a reciprocable feeder arranged to receive and feed one display object at a time from said guiding means to said conveyor, and feeder operating mechanism connected in timed relationship with said conveyor, said feeder having a display object interceptor at the rearward portion thereof and movable therewith to intercept and transfer the conveyed display object from the rearward section of said conveyor to said guiding means in response to the retraction stroke of said feeder.

12. An exhibiting or display device comprising a plurality of display objects, an endless conveyor or having an upwardly movable front section and a downwardly movable rear section, spaced display object carriers thereon engageable with said display objects for conveying each display object from a display location near the front of the device around to a storage location nearer the rear thereof, spaced upper and lower display object guiding means extending from said storage location toward said display location, a reciprocable feeder arranged to receive and feed one display object at a time from said upper guiding means to said conveyor, feeder operating mechanism connected to said feeder and operable in timed relationship with said conveyor, and a display object separator operably connected to said feeder and interposable in response to the motion of said feeder between the lower portion of the foremost display object and the lower portions of the other display objects while urging the lower portion of said foremost display object from said lower guiding means toward said conveyor into position for conveyance by said conveyor.
